W. T. PITTMAN.
DOUBLE ACTING PUMP JACK.
APPLICATION FILED AUG. 16, 1911.

1,028,959.

Patented June 11, 1912.

UNITED STATES PATENT OFFICE.

WILLIAM T. PITTMAN, OF FORT WORTH, TEXAS, ASSIGNOR TO CRESCENT PUMP WORKS, OF FORT WORTH, TEXAS, A CORPORATION OF TEXAS.

DOUBLE-ACTING PUMP-JACK.

1,028,959.

Specification of Letters Patent. Patented June 11, 1912.

Application filed August 16, 1911. Serial No. 644,291.

To all whom it may concern:

Be it known that I, WILLIAM T. PITTMAN, a citizen of the United States, residing at Fort Worth, county of Tarrant, State of Texas, have invented certain new and useful Improvements in Double-Acting Pump-Jacks; and I do hereby declare the following to be a full, clear, and exact description of the invention, such as will enable others skilled in the art to which it appertains to make and use the same.

This invention relates to double acting pump jacks of the type used in connection with Artesian or other wells, and the object of the invention is to provide a perfectly balanced pumping apparatus of efficient and durable construction, all of the working parts of the device for operating the pump rods being above the ground level and so arranged with reference to each other as to be easily accessible for inspection and repair.

My improved pump operating mechanism also has the advantage that it embodies a minimum number of parts, and that the pump rods can not only be very easily attached to and detached from their respective cross heads but also removed from the well when so detached, without dislocating the cross heads or otherwise disturbing the main operative parts of the apparatus. After the rods have been detached from their cross heads they can be moved through the latter and out of the well without interference with or detachment of the cross head operating means or other elements of the mechanism.

The novel features of the invention will appear clearly from the following description and claims.

40 In the accompanying drawing, Figure 1 is a front elevation of a pumping jack embodying the invention; Fig. 2 is a side elevation of the same; and Fig. 3 is a top plan view of the jack.

45 Referring to the drawing, which shows the preferred embodiment of the invention, it will be seen that the operative parts of the pump jack are supported on a bed plate A, which, in practice, is situated at the level 50 of the ground, and is provided with a suitable opening for telescoping pump rods S, T, which project above the bed plate or foundation to a certain extent and are reciprocated in a vertical direction by means

of cross heads C' C respectively. These cross heads are driven from a main driving shaft R which is journaled horizontally in suitable bearing members M on the bed plate A, said driving shaft having an intermediate pulley D for a suitable driving belt, and being detachably positioned in the bearing members or pillow blocks M by means of removable cap pieces A', as shown. In the embodiment illustrated, the driving shaft R carries four pinions Q, arranged in pairs 65 at opposite sides of the driving pulley, the pinions of each pair being at opposite sides of one of the bearings for the shaft. Each of the pinions Q meshes with a large gear wheel E fixed to a driven shaft X. One of these shafts X is journaled in each of the bearings M, at opposite sides of the driving pulley D, and each such shaft carries two of the gear wheels E, one at each end, i. e. at opposite sides of the corresponding bearing. The end gear wheels E serve to drive the upper cross head C, by means of connecting rods or pitmen F connected with suitable wrist pins on said gear wheels, as indicated at I, said pitmen having their upper 70 ends swiveled to the outer ends of the cross head C, as indicated at Y. The wrist pins on said outer gear wheels are in line with each other, i. e., lie in the same horizontal plane, and they are located diametrically 75 opposite to other wrist pins on the inner gear wheels E, said last named wrist pins being connected with the intermediate portion of the lower cross head C' by means of pitmen G. In this way, the cross heads are 80 driven oppositely, and as said cross heads and the parts carried thereby are given such relative weight as to make the two driven elements of the mechanism of the same weight, it will be understood that a perfect 85 balancing of the apparatus can be obtained. In the embodiment shown the upper cross head C is longer and heavier than the lower cross head C', but this is compensated for by placing the light inner pump rod T on the head C and securing the heavier outer pump rod S to the head C', the weight of the said parts being so chosen as to effect the result just noted.

One of the important features of my invention is that the cross heads are mounted and guided above the driving and driven shafts, and that the same guide rods are 105

used for both cross heads. It will be noted that the driven shafts are positioned detachably in the bearings M by means of cap pieces B, and these cap pieces are used 5 to support upwardly directed guide rods N, as shown in Fig. 1. The ends of the lower cross head C' embrace said guide rods, as shown at C², while the upper cross head C is guided on said rods by means of suitable 10 openings located between the ends of said head and the middle portion thereof, as indicated at C³. The lower ends of the guide rods N, one of which projects upward from each bearing of the bed plate, are offset 15 slightly from a line connecting the centers of the wheels E, as shown in Fig. 2.

In order to hold the rods N firmly in the position indicated, each of the same is braced by means of an inclined brace rod O, 20 the upper end of which is suitably secured at P to the upper portion of the corresponding guide rod, while the lower end is suitably supported on and secured to the adjacent bearing block.

25 The pump rods S, T are secured to the respective cross heads by the following mechanism: The intermediate portion of the cross head C is enlarged to a certain extent and provided with an opening J' which is 30 sufficiently large not only to permit the rods S, T to be drawn through the same but also the pump casing itself. A similar opening K' is formed in the intermediate portion H of the cross head C' in line with the opening J'. The rod T is detachably applied to the cross head C by means of caps or plates J seated over the respective ends of the opening J and each having a central opening in which the rod T is secured in the desired 40 adjustment in any suitable manner, as by the nuts J² shown in the drawing. The tubular rod S is similarly secured in caps or plates K by means of nuts W', said caps or plates overlying the opposite ends of the 45 opening K' in cross head C'. It will therefore be understood that with this construction the pump rods can be detached from the cross heads by loosening the fastening nuts, whereupon the plates covering the respective 50 openings in the cross heads can be removed, with the result that the pump rods and even the pump casing and its adjunctive parts can be withdrawn in a vertical direction through the cross heads without necessitating the detachment of the latter or any disturbance whatever of the main operating elements of the mechanism. This is one of the substantial advantages provided by my invention, and a further advantage resides in the fact that all of the 55 parts can be made strong and durable, the arrangement being such that they are all easily accessible by the attendant. The inner rod T is guided in a stuffing box W carried by the lower cross head, preferably at

a point above the top plate K. The stuffing box for the outer rod S is shown at V. The pump casing can be supported from the bed plate in any convenient manner, and for that reason I have not deemed it necessary 70 to describe the pump casing and its supporting means, as the character of these will be entirely familiar to those skilled in the art. It will be understood, however, that the casing must be detachably secured in the bed plate in such a manner as to permit the withdrawal of such casing upward through the cross heads, in the manner hereinbefore indicated.

75 One of the most important advantages of the improved pump jack is that the heavier parts are set directly on the base plate or bed close to the ground, so that there are no weighty parts projecting high in the air, which is a disadvantage of some pump 80 jacks heretofore devised; and at the same time it is not necessary for me to arrange some of the driving parts of the jack, such as the connecting rods and cross heads, below the ground level, which is a defect of 85 other prior pump jacks by reason of the fact that when said parts are so located they are more or less inaccessible for inspection and repair. With the improved construction described above, all of the 90 driving elements are so located that they can be easily reached by an operator standing on the ground adjacent the bed of the apparatus, and the stuffing boxes for the respective pump rods are likewise accessible 95 under these conditions.

100 Of course I have not attempted to describe or illustrate the numerous modifications of the device which may be made without departing from the invention, the scope 105 of which is defined in the claims.

The stub shafts X form in reality sections of a single horizontal shaft driven by the driving shaft, especially in view of the fact that said sections are interconnected at their 110 adjacent ends through the lower cross head.

What I claim is:—

1. In a double acting pump jack, the combination of a bed, guide rods rising therefrom, a horizontal shaft journaled in the 115 bed and carrying wheels arranged in pairs, the wheels of each pair being at opposite sides of one of the guide rods, and cross heads guided vertically on said rods, one above the other, one of said cross heads 120 being connected to the end wheels of the series and the other cross head being connected with the intermediate wheels.

125 2. In a double acting pump jack, the combination of a bed, guide rods rising therefrom, a horizontal shaft journaled in the bed and carrying four gears, a driving shaft journaled in the bed and having pinions meshing with the respective gears, a cross head guided on said rods and connected 130

with the end gears, and a second cross head guided on said rods and connected with the intermediate gears.

3. In a double acting pump jack, the combination of a bed a driving shaft journaled horizontally therein, a driven shaft journaled in the bed parallel to the driving shaft and carrying four wheels arranged in a longitudinal series, upright guide rods rising from the bed between the intermediate and end wheels, an upper cross head guided on said rods and connected by pitmen with the end wheels, and a lower cross head guided on said rods and connected by pitmen with the intermediate wheels.

4. In a double acting pump jack, the combination of a bed, a driving shaft journaled horizontally therein and carrying four pinions, a driven shaft journaled in the bed parallel to the driving shaft and carrying four gears meshing with the respective pinions, guide rods rising from the bed, a pump-rod-carrying cross head guided by said rods and connected with the end gears on said driven shaft, and a second pump-rod-carrying cross head, below the first, guided on said rods and connected with the intermediate gears of the series.

5. In a double acting pump jack, the combination of a bed, guide rods rising therefrom, a relatively long cross head guided on said rods at points between the center of said head and the ends of the same, whereby the ends of the cross head project laterally beyond the guide rods, a second, relatively short cross head having its ends embracing the guide rods below the first named cross head, pump rods carried by the respective cross heads and telescoping with each other, and means to operate the cross heads oppositely.

6. In a double acting pump jack, the combination of upright guide rods, a relatively long cross head guided on said rods and projecting at its ends beyond the same, an inner pump rod carried by said cross head, a relatively short cross head guided on said rods and having its ends embracing the latter, an outer pump rod of tubular form carried by said last named cross head and surrounding the inner pump rod, and means to actuate said cross heads oppositely, as described.

7. In a double acting pump jack, the combination of upright guide rods, a relatively long cross head guided on said rods and projecting at its ends beyond the same, a pump rod carried by said cross head, a relatively short cross head guided on said rods adjacent the first cross head and having its ends embracing the respective rods, an outer tubular pump rod on the short cross head, surrounding the first mentioned pump rod, a horizontal shaft below both cross heads and carrying two pairs of

wheels, the wheels of each pair being located at opposite sides of one of the guide rods, means connecting the end wheels of the series with the long cross head, and means connecting the intermediate wheels of the series with the short cross head.

8. In a double acting pump jack, the combination of a base, upright guide rods rising therefrom, cross-heads guided on said guide rods, one above the other, a horizontal shaft journaled on the base below the cross-head, means for driving said shaft, connections between the respective ends of said shaft and the upper cross-head, and connections between the shaft and lower cross-head intermediate the first named connections.

9. In a double acting pump jack, the combination of a bed, upright guide rods rising therefrom, cross heads guided on said rods, one above the other, a horizontal shaft journaled on the bed below the cross-heads, means for driving said shaft, wheels on the end portions of said shaft, pitmen connecting the respective wheels with the ends of one of the cross heads, and an operative connection between the intermediate portion of said shaft and the intermediate portions of the other cross head.

10. In a double acting pump jack, the combination of a bed, upright guide rods rising therefrom, pump-rod-carrying cross heads guided on said rods, one above the other, a driving shaft journaled horizontally on said bed and carrying four pinions, a driven shaft journaled horizontally on said bed parallel to the driving shaft and carrying four gears meshing with the respective pinions, both of said shafts being located below the cross heads, and means connecting the end gears with one cross head and the intermediate gears with the other cross head.

11. In a double acting pump jack, the combination of a bed, upright guide rods rising therefrom, cross heads guided on said rods, one above the other, a horizontal shaft journaled on the bed below said cross heads, means for driving said shaft, wheels on the intermediate portion of said shaft, each operatively connected with the lower cross head, and operative connections between the respective end portions of the shaft and the upper cross head.

12. In a double acting pump jack, the combination of upright guide rods, cross heads guided on said rods and having alined openings, and means to detachably secure pump rods in the respective openings, the pump rods when detached being movable upwardly through both of said openings and out of the well.

13. In a double acting pump jack, the combination of upright guide rods, cross heads guided on said rods and having alined

openings, and means to secure detachably inner and outer pump rods in the respective openings, the latter being of such size that when the pump rods are detached the same 5 together with the pump casing can be moved upwardly through the cross heads and out of the well.

14. In a double acting pump jack, the combination of a bed, upright guide rods 10 rising therefrom, a shaft journaled horizontally on said bed, upper and lower cross heads guided on said rods, the upper cross head extending laterally at its ends beyond the guide rods, means connecting the ends 15 of said upper cross head to said shaft, and means connecting the intermediate portion of the lower cross head to said shaft.

15. In a double acting pump jack, the

combination of a bed, upright guide rods rising therefrom, an upper cross head 20 guided on said guide rods and extending at its ends laterally beyond said rods, a lower cross head guided on said rods, a horizontal shaft journaled on the bed, means connecting said lower cross head with the 25 intermediate portion of said shaft, wheels on the ends of said shaft, and pitmen connecting said wheels with the respective ends of the upper cross head.

In testimony whereof I affix my signature, 30 in presence of two witnesses.

WILLIAM T. PITTMAN.
